SLICING MACHINE WITH STACKER

Adrianus van Duyn, Hillegersberg, Rotterdam, Netherlands, assignor to U. S. Slicing Machine Company, Inc., La Porte, Ind., a corporation of Indiana

Application August 4, 1947, Serial No. 766,027
In the Netherlands January 23, 1942

Section 1, Public Law 690, August 8, 1946
Patent expires January 23, 1962

4 Claims. (Cl. 146—94)

1

This invention relates to slicing machines of the type having slice-stacking mechanism including a rotatable slice conveyor, of the type disclosed in the Van Berkel Patent No. 2,277,279.

In such machines, the conveyor may have spikes which impale the slices in succession and convey them for discharge in succession upon a slice receiver. In machines having such a conveyor, it is customary to provide at the back of the slicing knife, a slice guide with a curved surface which presses each slice upon the conveyor spikes, the guide being formed with grooves or slots along which the spikes pass during the slice-pressing action.

The object of the invention is to provide in the conveyor drive a safety device in order to prevent breakage of or damage to the driving mechanism in the event that movement of the conveyor is obstructed. For instance, such an obstruction might occur with a spiked conveyor in the event that a conveyor spike got bent and fouled the slice guide.

The invention comprises a slicing machine of the type stated in which there is interposed between the conveyor and its driver a yielding device by virtue of which the driver is rendered ineffective in relation to the conveyor if rotation thereof is resisted.

The invention also comprises a slicing machine of the type stated in which the conveyor is connected to its driver by mechanism comprising pivotal members interconnected by a yielding device by virtue of which one of said members is movable in relation to the other so as to render the mechanism ineffective if rotation of the conveyor is resisted.

The yielding device may be a spring which normally maintains a one-way driving connection between the driver and the conveyor, during the slice conveying motion, but yields to resistance imposed upon the conveyor, thus permitting the driver to continue its movement idly.

The driver and the conveyor may be connected through two oscillatory connectors, one of which has an abutment normally engaged by the other under the action of the yielding device, the arrangement being such that the connector connected to the conveyor stops its motion if the conveyor is stopped during the slice conveying motion by resistance, whereas by virtue of said device the connector connected to the driver continues its motion.

A slicing machine embodying the invention will now be described by way of example with reference to the accompanying drawing in which:

2

Fig. 1 is an elevation of parts of the machine as viewed from the back of the knife; and

Fig. 2 is a corresponding view showing the safety device in operation.

Fig. 3 is a top plan view of the machine in normal operation.

In the example, the slicing machine includes as usual a rotatable circular knife 2, the axle 1 of which is driven by a motor or by hand, being journaled in a knife bracket (not shown) forming a component of the frame of the machine. The substance to be sliced is carried on a carriage 3 which is reciprocable past the front of the knife.

The drive of the slice conveyor includes a pinion 4 on the knife axle 1, said pinion meshing with a gear wheel 5 on a shaft 6. This shaft has a disc 7 in which is formed a cam groove engaged by a cam-following roller 8 journaled at one end of a lever arm 9. This lever arm is associated with another lever including an arm 9A, the end of which is pivotally connected to a link 10 which, in its turn, is pivotally connected to a horizontally reciprocable rack 11. This rack 11 meshes with a pinion 12 on the shaft 13 of the slice conveyor 15, as shown clearly in Fig. 1. The slice conveyor 15 may be of known construction; it includes spikes which, in order to pierce each successive slice, cooperate with a slice guide 18 mounted behind the knife adjacent to the cutting arc thereof. The slice guide 18 is formed with grooves or slots 25 which are entered by the conveyor spikes during their slice piercing action.

The lever arm 9 is connected through a safety device (hereinafter described) to the lever including the arm 9A. The cam disc 7 may be regarded as the driver of the conveyor, the drive being transmitted to the conveyor through the mechanism described. The conveyor performs a to-and-fro rotational motion.

The conveyor is also associated with a slice discharging fly 14 which is turnable about a stationary pivot pin 16 and which is operatively connected through a link 17 to a lever 27 provided with a roller 28 serving as follower to a cam 26 on the shaft 6. The slice discharging action of the fly is effected by a spring (not shown), the function of which is to urge the roller 28 to maintain contact with the cam 26.

The machine also includes a slice receiver (not shown) which is provided at the level indicated by the line A in Fig. 1.

The previously mentioned lever including the arm 9A also has an arm 24 which extends along-

side the lever arm 9. Both levers are fulcrumed on the same stationary pin 19. A tension spring 20 connects a projection 21 on the lever arm 9 with a projection 22 on the other lever arm 9^A. Under normal working conditions the lever 9, projection 21 and the lever 9^A, projection 22, and arm 24 operate as a single unit, the arm 24 being maintained tightly against an abutment pin 23 of the arm 9 under the pull of the spring 20. During the slice conveying motion of the conveyor, the drive is transmitted through the spring 20, which must be strong enough to force the spikes to pierce the hardest and thickest slices. During the return motion the drive is transmitted through a pin 23 to the arm 24.

Suppose that the conveyor meets an obstruction during its slice conveying motion; suppose, for instance, one or more of the spikes foul the slice guide 18. In that event the spring 20 yields before the resistance caused by the obstruction, thus permitting the driver 7 to continue its rotation and the lever 9 to continue its movement about the fulcrum 19. On the other hand, the lever 9^A, projection 22, and arm 24 is stopped, so that the normal engagement between the abutment pin 23 and the arm 24 is interrupted. This condition of the parts is illustrated by Fig. 2, in which it will be seen that the arm 24 is held raised while the arm 9 has moved downwards under the action of the driver 7. Thus, when the safety device is brought into operation, the driver 7 is rendered ineffective in relation to the conveyor for the time being. As soon as the obstruction is removed, normal operation of the conveyor continues.

As aforesaid the machine shown in the drawing is an example. Accordingly, modifications may be made. The invention is applicable to slicing machines in general of the type stated.

Changes may be made in the form, construction and arrangement of the parts without departing from the spirit of the invention or sacrificing any of its advantages, and the right is hereby reserved to make all such changes as fall fairly within the scope of the following claims.

The invention is hereby claimed as follows:

1. In a slicing machine, a pivotally mounted slice receiver, a pivotally mounted first lever, a projection on said lever, means for actuating said lever, a pivotally mounted second lever, an operable connection between said second lever and said slice receiver, and resilient means normally maintaining a part of said second lever in abutment with the projection on the first lever whereby the second lever may be actuated by the first lever to pivot said slice receiver under normal operating conditions, but permitting the second lever to move out of engagement with said projection when the slice receiver is overloaded, thereby operably disconnecting the slice receiver from the said lever actuating means.

2. In a slicing machine, a pivotally mounted slice receiver, a pivotally mounted first lever, a projection on said lever, cam means for oscillating said lever, a pivotally mounted second lever,

an operable connection between said second lever and said slice receiver, and resilient means normally maintaining a part of said second lever in abutment with the projection on the first lever whereby the second lever may be actuated by the first lever to pivot said slice receiver under normal operating conditions, but permitting the second lever to move out of engagement with said projection when the slice receiver is overloaded or is being obstructed, thereby operably disconnecting the slice receiver from the said lever oscillating means.

3. In a slicing machine, a pivotally mounted slice receiver, a pivotally mounted first lever, a projection on said lever, cam means for oscillating said lever, a pivotally mounted second lever, an operable connection between said second lever and said slice receiver, and a spring operably connected between said levers and normally maintaining a part of said second lever in abutment with the projection on the first lever whereby the second lever may be actuated by the first lever to pivot said slice receiver under normal operating conditions, but permitting the second lever to move out of engagement with said projection when the slice receiver is overloaded or is being obstructed, thereby operably disconnecting the slice receiver from the said lever oscillating means.

4. In a slicing machine, a pivotally mounted slice receiver, a pivotally mounted lever, a projection on said lever, cam means for oscillating said lever, a bell crank pivotally mounted intermediate its ends, an operable connection between one arm of said bell crank and said slice receiver, and spring means normally maintaining the other arm of said bell crank in abutment with the projection on said lever whereby the bell crank may be actuated by the lever to pivot said slice receiver under normal operating conditions, but permitting the last said arm of the bell crank to move out of engagement with said projection when the slice receiver is overloaded or is being obstructed, thereby operably disconnecting the slice receiver from the said lever oscillating means.
